UNITED STATES PATENT OFFICE.

HERBERT L. PARKER, JR., OF ST. LOUIS, MISSOURI.

CLOTHESRACK.

Application filed July 2, 1923. Serial No. 649,142.

To all whom it may concern:

Be it known that I, HERBERT L. PARKER, Jr., a citizen of the United States, residing at St. Louis, Missouri, have invented a certain new and useful Improvement in Clothesracks, of which the following is a full, clear, and exact description, such as will enable others skilled in the art to which it appertains to make and use the same, reference being had to the accompanying drawing, forming part of this application.

My invention relates to clothes racks and consists in an improved folding device especially adapted to be used upon the wall or door of a closet and arranged so that it may be swung into one position so as to require a minimum amount of space for itself and clothing hung thereon or to be swung into another position to facilitate selection and removal of clothing hung thereon; this being the main object of my invention.

An additional object is to produce an attractive, strong, economical device of the nature described and one which will hold clothing when put away without one article of the clothing being disarranged by other articles on the hanger.

In the accompanying drawings which illustrate a selected embodiment of my invention—

Figure 1 is a vertical section through my rack when in storage position.

Figure 2 is a top view showing a section of the wall or door upon which the rack is mounted.

Figure 3 is a side view showing the rack in opened position.

Figure 4 is a fragmentary detail showing the construction of one of the parts referred to hereinafter.

The rack is preferably made of metal and consists of two channel-like sections 1 and 2 of about the same length and adapted to be nested together as best indicated in Figure 2.

A pin 3 extends through the flanges 4, 5, 6 and 7 of both sections 1 and 2 near their lower end to form a pivot or hinge on which section 2 may be swung from the vertical position indicated in Figure 1 to the horizontal position indicated in Figure 3. Each of the channel flanges is bent outwardly at its end as indicated at 8 and 9. This bending of the ends of the flanges makes the sections more rigid and affords a base for section 1 by which it may be attached to a

supporting surface A. A catch 10 is pivoted on section 1 near its upper end and is adapted to engage the upper end of web 11 of a section 2 when the latter is swung to the vertical position indicated in Figure 1. This engagement will be automatic when the rack is raised and will be easily released by lifting the projecting portion of the catch when it is desired to lower the rack. The web 11 of member 2 is provided with a series of parallel slits at spaced intervals throughout its length and the metal between these slits is bent outwardly as indicated at 12 leaving slots 13 of substantial width and varying lengths along the web. Two additional slots are indicated at 14, the metal of which is punched out and discarded.

U-shaped strips 15 are formed so as to be inserted through slots 13 and 14 from the back of the web and their bases are secured to the web intermediate said slots by rivets 16. They are also secured to the outwardly bent portions 12 of the web by rivets 17. The upper leg of each strip 15 is longer than the lower leg so that the hook 18 formed on the upper leg projects farther from section 2 than does the hook formed on the lower leg. The shorter leg of the middle U-shaped section is longer than the longer leg of the lower strip and, in turn, the shorter leg of the upper strip is longer than the longer leg of the middle strip. Hence when the rack is in closed position all of the hooks are out of vertical alignment and each end projects farther from the back of the rack than does the hook or hooks below it. This makes it possible for garments hung on the different hooks to swing free of each other or, at least, to hang without being crushed by the garments hung on the upper hooks. When member 2 is swung to a horizontal position the garments will be still farther spaced apart due to the spacing between the legs of the U-shaped strips and any garment may be removed without disarranging the others.

At 19 I indicate a flat strap of leather, canvas, or other material of such nature as to be flexible longitudinally when bent in one plane and to resist bending in a transverse plane. This strap serves to support member 2 in a horizontal position from member 1 which is secured to the wall or door. When the rack is folded up the characteristics mentioned will cause this strap to

fold, as indicated in Figure 1, in the space between the webs of sections 1 and 2 and without swinging to one side so as to be caught between the flanges 8 and 9 of the sections.

It will be noted that web 11 of section 2 terminates at 20 at its lower end a short distance above pin 3. When the section is lowered this end of web 11 is just in front 10 of the web section 1 and if strap 19 is loosened or broken this end of web 11 will engage the adjacent portion of the web of section 1 to prevent abnormal downward movement of the hooked section of the rack.

When my rack is folded up as shown in Figure 1 it occupies a small amount of space and any clothes hung thereon also take up little space, but the clothes on each hook will not be pulled out of shape by the presence of clothes on other hooks. When the device is opened out as indicated in Figure 3, an extended hanging space is provided so that the clothes on each hook may be easily examined and removed without disturbing 25 the clothes on the other hooks.

I claim:

1. In a metal clothes rack, a vertical member having pairs of parallel vertical slits at intervals, the metal strips between said slits 30 being severed at one end from said member and bent outwardly, and clothes suspending elements secured to said member and ex-

tending through the openings provided by said strips, the severed and outwardly bent ends of said strips being secured to said elements at points spaced from said member. 35

2. In a metal clothes rack, a channel-shaped element, the web of which is provided with spaced pairs of parallel slits, the metal between parallel slits being bent outwardly, a U-shaped strip, the base of which is secured to the back of said element web and the legs of which extend outwardly through adjacent apertures formed by the bending of the metal between the slits and 40 secured to said bent metal at a point spaced from the element web, and hooks formed on the ends of the legs of said strip. 45

3. In a metal clothes rack, a channel-shaped element, the web of which is provided with a series of pairs of parallel slits at intervals, the metal between parallel slits being displaced, U-shaped strips, the bases of which are secured to the back of the web of said element between said slits and 50 the legs of which extend outwardly through adjacent apertures formed by the bending of the metal between the slits, the legs of said strips increasing in length from one end of said element to the other, and hooks 55 formed on the ends of the legs of said strips. 60

In testimony whereof I hereunto affix my signature this 27th day of June, 1923.

HERBERT L. PARKER, JR.
